UNITED STATES PATENT OFFICE.

EMILE JOHN WELFFENS, OF MANCHESTER, ENGLAND.

SLUBBING, ROVING, AND LIKE FRAME.

Application filed August 2, 1918. Serial No. 247,934.

To all whom it may concern:

Be it known that I, EMILE JOHN WELFFENS, a subject of the King of the Belgians, residing at 8 Mauldeth Road west, Withington, Manchester, in the county of Lancaster, England, have invented new and useful Improvements Relating to Slubbing, Roving, and like Frames, of which the following is a specification.

10 This invention relates to the winding gear responsible for the up and down motion of the top or bobbin rail and for the excess speed of the bobbins or flyers in slubbing, roving and like frames and wherein both the 15 excess speed and the up and down motions are controlled by cone or equivalent governing gear. The excess speed is obtained through the differential, the up and down motion through an appropriate train of 20 gearing. One of the motions of the differential and the gear train operating the up and down or lifting motion are driven—through gearing—from the bottom cone or equivalent member of the governing gear. 25 For perfect operation the excess speed and lifting motions should be intimately interdependent and the duty of the cone or equivalent gearing should be one of governing and of governing only. In frames as heretofore 30 constructed the excess speed and lifting motions are not intimately interdependent and the entire load due to the up and down or lifting motion is thrown upon the governing gear. The speed of the shaft operating 35 the gear train responsible for the lifting motion, which shaft is driven from and by the governing gear, is usually such that it entails considerable gearing down in the train which it operates and the mechanism for reversing the direction of travel of the 40 top or bobbin rail is usually directly driven from that shaft. The combination is one from which backlash cannot be eliminated. By providing a slow initial speed for that 45 shaft the gear train operating the lifting motion may be simplified because less gearing down will be required. Instead of the bevel gearing at present used for the reversing mechanism I may use epicyclic tumbler 50 reversing gear, this reversing gear may be located nearer to the shaft carrying the pinions which mesh with the racks fixed to the bobbin rail and the whole train may be rendered much more compact and formed 55 into a combination from which backlash is almost entirely excluded. The method heretofore in use of operating the winding does not allow any variation in the bobbin gear train without corresponding modifications in other parts of the frame gearing. There 60 are cases where this operates against improving the machine by replacing one gear train by another such for example as replacing a spur gear train by a chain gear train. Neither does this method allow of governing 65 gear, possessing a speed ratio greater than the ratio between minimum and maximum diameters of the bobbin to be wound, being used to its full advantage nor does it allow of applying governing gear having the customary speed ratio to the winding of bobbins with a diameter ratio exceeding that of the governing gear. It likewise precludes the use of governing gear with a speed ratio below the normal for the winding of bobbins having a normal diameter ratio. 70

75 It is the object of this invention to modify the wheel train responsible for the lifting motion and to provide a novel method of operating same. This method severs all direct connection between the governing gear and the lifting motion and in frames provided with modern differentials, relieves the governing gear of the major part of the driving load resulting from same. It allows 80 the shaft driving the gear train responsible for the lifting motion to rotate very slowly, and thereby renders the simplification of this train practicable and secures a more intimate and positive interdependence of 85 the excess speed and lifting motions through the resultant elimination of backlash. It renders slight variations in the ratio of the bobbin gear possible without requiring variations in other parts of the frame gearing 90 and its application admits the use, to its full advantage, of governing gear the speed ratio of which is not the same as the ratio between minimum and maximum diameters of the bobbins to be wound. 95

100 According to the present invention these results are obtained by altering the combination of the wheel train responsible for the up and down motion of the bobbin rail, by 105 modifying the gear controlling the reversing motion comprised in this train, and by imparting to a shaft controlling this train a motion of an aggregate character resulting from two different driving motions, operating at different initial and subsequent ve- 110

locities, acting at the same instant of time upon gearing suitably fixed to that shaft. The first driving motion is obtained from the main driving shaft, the second driving motion from the member of the differential which gears with the bobbin train. The two driving motions are so geared that their motions are concentrated upon one or more wheels fixed to the shaft. The motion derived from the main shaft is one of constant speed, the motion obtained from the differential member is one of variable speed, the speed varying in accordance with the action of the differential. The invention will be explained by reference to the accompanying drawings and by citing cases. The drawings are diagrammatic, but they illustrate clearly the principles as embodied in the invention. The cases cited do not purport to be actual working conditions. They indicate substantially the nature of the defects and the limitations encountered in winding gearing as at present applied and which the new method is designed to eliminate or remove. When the explanation is understood, no difficulty will arise in applying the new method to any machine coming within the scope of my invention. For the purpose of explanation I have assumed the bobbin leading, a roving requiring 9 layers per inch, a spindle speed of 500 R. P. M. a minimum bobbin diameter of $1\frac{3}{4}$ inches and a maximum one of 6 inches, a bottom cone speed of 484.5 R. P. M. for a $1\frac{3}{4}$ inches diameter of bobbin with the corresponding speed of 139.71 R. P. M. for a 6 inches diameter, a differential in which the train of reducing wheels has a value of two twenty-fifths, a main shaft speed of 282.6 R. P. M., lifting speeds of the bobbin rail of 10.252 inches per minute maximum and 2.99 inches minimum, for the member of the differential gearing with the bobbin train a maximum speed of 308 R. P. M. and a minimum speed of 274 R. P. M. and frame gearing to make the machine operate substantially correctly with the given conditions. When citing normal or customary ratio, a 4 to 1 ratio is implied both for governing gear speed and for bobbin diameter. This speed ratio is fairly normal for governing gear, whereas a 4 to 1 ratio between minimum and maximum bobbin diameters is not usual in practice, though it obtains and is sometimes exceeded. It may here be stated that it is well known that, when winding, the bobbin speed and the lifting motion speed must vary inversely as the bobbin diameter and that, for proper operation, the governing gear speed must vary in a like manner in frames as built at present.

Referring to the drawings:—

Fig. 1 is a fragmentary front elevation illustrating the bobbin rotating and elevating mechanism of a slubbing or roving machine embodying one form of my improved

mechanism for controlling the elevating gearing;

Fig. 2 is a view similar to Fig. 1 illustrating my improved mechanism for reversing the motion of the elevating mechanism, and a slightly modified form of controlling mechanism;

Fig. 3 is a partly sectional view, on a considerably enlarged scale, taken approximately on the line 3—3 of Fig. 2; and

Fig. 4 is an end view of the mechanism shown in Fig. 3.

Similar characters of reference designate corresponding parts in the different figures of the drawings.

Referring to the drawings, and especially to Figs. 1 and 2, A designates the main driving shaft, which carries a differential, designated herein generally by the reference character 9, which differential is common in machines of this character. Machines showing the general arrangement of mechanisms of which the present invention is an improvement, are illustrated in the patents to Campbell, No. 511,725, dated December 26, 1893, Fossel, No. 596,106, dated December 28, 1897, and Shaw, No. 479,108, dated July 19, 1892.

The shaft A imparts motion by means of gearing 16 to what is commonly known as the governing gear, and comprises the upper and lower cone pulleys 7 and 8 connected by a belt 6, and which governing gear in turn transmits motion by means of a train of gearing 12 to the variable speed member 11 of the differential. The top or bobbin rail, designated herein by the reference numeral 5, carries the bobbin 14, which is adapted to receive rotary motion from the differential member 10 through an intermediate train of gears 13 and a pair of bevel pinions 27 and 28. To the bobbin rail 5 is secured a depending rack bar 4 in mesh with a pinion 23^a secured to one end of a shaft 23^b, the opposite end of which carries a pinion 23 by means of which the bobbin rail is vertically reciprocated in the manner hereinafter described. All of the mechanism above described is old and well known in the art, and forms no part of the present invention.

To the shaft A is secured a gear 15, in mesh with which is a gear 17 mounted for rotation on a shaft 1, said shaft also carrying loosely mounted thereon a gear 18 in mesh with an idler pinion 19, which in turn meshes with a pinion 20 carried by the member 10 of the main shaft differential. The gears 17 and 18 each carry a bevel crown 17^a and 18^a respectively, between which mesh a pair of bevel star pinions 21 and 22 mounted for rotation on studs extending from the shaft 1, thus forming a second differential, the shaft 1 being the recipient of the aggregate motion of the

gears 15 and 20 carried by the driving shaft A. This mechanism is the same in Figs. 1 and 2, the purpose of shaft 1 in both figures being to operate the gearing which 5 causes the vertical motion of the bobbin rail.

In the structure shown in Fig. 1, the shaft 1 has secured thereto a bevel pinion 3 in mesh with one crown of a double bevel gear 3^a, the other crown of which lies 10 between a pair of sleeve connected bevel gears 33, which are slidable upon a shaft 33^a, and which shaft carries at its opposite end a pinion 33^b in mesh with a pinion 24^a secured to one end of a shaft 24^b, which carries at 15 its opposite end a pinion 24 in mesh with an idler pinion 24^c, which in turn meshes with the pinion 23 hereinbefore described. It will readily be seen that the direction of movement of the rack bar 4 will depend 20 on which of the sleeve connected gears 33 is in mesh with the pinion 3^a, it being understood that a suitable clutch is employed for shifting the gears 33 on the shaft 33^a, and which clutch is usually operated in mechanisms of this character by means of the "building motion", the clutch having been omitted from the drawings for the sake of clearness.

In the form shown in Fig. 2 motion is 30 transmitted to the bobbin elevating gearing in a slightly different manner. In this case, a gear 55 is secured to shaft 1, which gear meshes with a gear 57 secured to a shaft 45, which carries at its opposite end 35 a gear 30 adapted to mesh either directly with a gear 25 or through an intermediate idler 26 (see Fig. 3), and which idler, in turn meshes with the gear 23 hereinbefore described. This form of reversing mechanism, which I have termed herein a "tumbler gear", includes a plate 29 on which is mounted for rotation an eccentric sheave 31 carried by a stud 32 secured to the plate 29, said plate being provided with a pair of adjustable stops 47 and 48 for controlling the rotation of the sheave in opposite directions. The pinion 26 is carried on a sleeve secured to one end of a link 50, the opposite end of which engages the eccentric 43 31, on which pinion 25 is mounted for rotation, and connected to the sleeve on which the pinion 26 is mounted is a second link 49, which carries at its opposite end the stud shaft 45 on which the gear 30 is mounted 45 for rotation. The entire tumbler gear just described is carried by a frame 51 and is operated from the building motion in the manner hereinafter described. A cable 35 passes over the pulley or sheave 31 and has secured to one end thereof a weight 36, the opposite end of the cable passing under a pulley 42 and over pulleys 43 and 34 (see Fig. 2) and is secured to what is 50 known as the "traverse" 40 which is common in machines of this character. The

pull of weight 36 is counter-balanced by weight 37 secured to the end of a cable 38 which passes over a pulley 41 mounted on said traverse and around the pulley 34, the end of the cable 38 being secured in like 70 manner to the traverse 40. The pulley 34 being adjustably carried by an arm 52, which is adapted to be moved right and left of Fig. 2 by the building motion, and thus cause the sheave 31 to rotate and the pinions 75 25 and 26 to alternately engage with gear 23, thereby giving to the bobbin rail 5 the vertically reciprocating motion necessary.

The sum:—lowest speed of shaft 1 plus difference between maximum and minimum speeds of member 10 must equal the highest speed of shafts 1 and the maximum and minimum speeds of shaft 1 must be in inverse ratio to the bobbin diameters. Whenever this condition is satisfied correct up 80 and down motion will be obtained provided the differential on the main shaft A communicates the correct excess speeds to the bobbins. To determine the correct lowest speed for shaft 1, the following method may 85 be employed:—

The difference between maximum and minimum bobbin diameter gives the number of turns difference I would obtain with shaft 1 running at these speeds and 90 by adjusting the value represented by the minimum diameter of the bobbin so that the correct number of turns difference is obtained. I comply with the conditions given above. In the case cited the bobbin diameters are 1 $\frac{1}{4}$ inches and 6 inches, fractionally 7/4ths and 24/4ths. So the diameter ratio is 7:24. The difference between these two values 24—7=17 represents the turns difference obtained with shaft 1 running at 24 R. P. M. and 7 R. P. M. respectively. From the case cited we know the speeds of member 10 to be 308 R. P. M. and 274 R. P. M. 308—274=34 R. P. M. is the difference I require between maximum and minimum speeds of shaft 1. Now if 100 17 turns difference are obtained by 7 turns of lowest speed 34 turns will be obtained by 105

$$\frac{7 \times 34}{17} = 14 \text{ turns of lowest speed.} \quad 115$$

14 plus 34 = 48 turns will according to condition laid down above constitute the highest speed of shaft 1. Now 48 and 14 have 120 obviously the same ratio as 24 and 7 and the speed will vary inversely as the bobbin diameters. The required conditions obtain and correct up and down motion would result. The speed of wheel 17 may be geared down so that the desired conditions obtain 125 when wheel 18 is running at a speed equal to member 10 or, wheel 17 may run at main shaft speed whilst the speed of wheel 18 is geared up so as to make the required conditions result. Again both wheel 17 and 130

wheel 18 may be run at speeds different from those of the members which drive them. Whatever the type of differential on shaft 1, whatever the combination of 5 gearing employed and no matter whether the frame be bobbin or flyer leading; as long as the conditions laid down are satisfied correct up and down motion will result. 308-48=260 R. P. M. and 274-14=260 10 R. P. M. likewise, this being the speed at which wheel 17 should be run to obtain correct operation with wheel 18 running at speeds equal to those of wheel 20. With main shaft A running at 282.6 R. P. M., 46 15 teeth for wheel 15 and 50 teeth for wheel 17 would be found to give substantially 260 R. P. M. as required.

Where it is desired to run wheel 17 at main shaft speed, the reciprocal of the above gear 20 ratio namely 50 teeth for wheel 20 and 46 teeth for wheel 18 would be found substantially correct. This disposes of the case where the only modification desired, in an otherwise correctly operating frame, is the severance of 25 the lifting motion from the governing gear. Next, take the case where it is desired to utilize substantially fully a governing gear with a speed ratio of 4 to 1 for the winding of bobbins with a diameter ratio of substantially 30 2.7 to 1, such conditions being applicable for example where fine rovings are worked. The speeds may not be those obtaining in practice but the principle involved remains the same. By changing the bobbin 35 gear train wheels 10 and 13 from 50 and 52 to 70 and 71 teeth, we would require, for winding the above bobbins, speeds for cone 8 of 396.53 R. P. M. and 107.551 R. P. M. respectively, thus substantially utilizing the 40 full range of the governing gear. This modification would require member 10 to run at 300.374 R. P. M. and 270.8174 R. P. M. for correct operation. 300.374-270.8174=29.5566 R. P. M. The bobbin ratio is here 2.7 to 1 45 thus 2.7-1=1.7 of turns difference would be obtained for every turn of slow speed for shaft 1. 29.5566:1.7=17.3862 R. P. M. slowest speed of shaft 1. 29.5566 plus 17.3862=46.9428 R. P. M. highest speed of shaft 1. 50 46.9428 and 17.3862 have the same ratio as the bobbins 2.7 to 1. The speed varies inversely as the bobbin diameters and correct lifting motion will result. With main shaft A running at 282.6 R. P. M., 43 teeth for 55 wheel 15 and 48 teeth for wheel 17, the required speed of 270.8174-17.3862=253.43 R. P. M. would be substantially obtained. Where it is of advantage to run wheel 17 at main speed shaft the reciprocal of the gear 60 ratio indicated namely 48 teeth for wheel 20 and 43 teeth for wheel 18 would again be found to give substantially correct results. To follow the case will be considered where it is desired to employ a governing gear with a 4 to 1 speed ratio for winding bobbins hav-

ing a 4.5 to 1 diameter ratio. Such conditions may obtain when spinning coarse counts. By changing the bobbin gear train wheels from 50 and 52 to 50 and 53 teeth we would require, to wind the above bobbins, for cone 8 speeds of 529.595 R. P. M. and 153.735 R. P. M. respectively, thus speeds well within the range of a 4 to 1 governing gear. This would require member 10 to have speeds of 313.922 70 R. P. M. and 275.653 R. P. M. respectively. 313.922-275.653=38.269 R. P. M. The bobbin ratio is here 1 $\frac{1}{4}$ inches and 7.875 inches or 4.5 to 1 thus 4.5-1=3.5 of turns difference for every turn of slow speed for shaft 1. 38.269:3.5=10.922 R. P. M. slowest speed of 75 shaft 1. 38.269 plus 10.922=49.191 R. P. M. maximum speed of shaft 1. 49.191 and 10.922 have substantially the same ratio as the bobbin diameters. The speed varies inversely and correct lifting motion will be obtained with 80 main shaft A running at 282.6 R. P. M. and 59 teeth for wheel 15 and 63 teeth for wheel 17 as the required speed of 275.653-10.922=264.731 R. P. M. will be obtained substantially. Again with wheel 17 running at main shaft speed the reciprocal of the gear ratio indicated namely 63 teeth for wheel 20 and 59 teeth for wheel 18, would give results very 85 substantially correct.

Where still greater accuracy than that obtained is desired, it may be obtained by using compound instead of simple gearing in trains 90 15 to 17 and 18 to 20. I have spoken of the speeds of shaft 1 as those obtaining. It will be obvious that it is their ratio which will obtain as the actual speed shaft 1 will depend upon the planetary gear it carries.

In the foregoing examples the ratio of the 95 wheels in the bobbin gear train has been altered for the purpose specified. It will be obvious that that ratio might be altered in order to substitute a chain gear train for a spur gear train and that correct operation of the lifting motion may still be obtained. The 100 reason why it may be necessary to modify the ratio when employing a chain gear train lies in the fact that, on account of the considerably coarser pitch of the chain wheel teeth, it is much more difficult to obtain the 105 correct ratio if wheel diameters are to be kept within practicable limits.

It is well known that there are modern 110 differentials in use which with difficulty allow of very accurate operation on account of the train of reducing wheels incorporated in them. For example, instead of giving with the governing gear at a standstill, exactly 500 R. P. M. to the bobbins, they may only give 499.95 R. P. M. thus .05 R. P. M. short. 115 Where it is desirable to eliminate this defect, say for very fine rovings, my method of controlling the lifting motion provides a means as will be deduced from the foregoing and to which I will allude again later on.

I have stated that the motion of shaft 1 120

should be one of an aggregate character and the gearing mounted upon that shaft will be found one which produces this motion by rolling. I have stated that in frames 5 provided with modern differentials, my method relieves the governing gear of the major part of the driving load due to the lifting motion. It should be observed that a Houldsworth differential merely constitutes an effective means of producing the required variation in bobbin speed and that since the combination has no train of reducing wheels, it neither gives mechanical advantage nor takes strain off the governing gear whereas a differential comprising a reducing wheel train, does both. With a Houldsworth differential and my new method of operating the lifting motion the whole load due to both the bobbin motion 10 and the lifting motion would still have to be sustained by the governing gear while with my method of operating the lifting motion and a differential incorporating a train of reducing wheels only a certain percentage of the loads created by these motions would recoil upon the governing gear and this percentage would depend upon the value of the reducing wheel train. I have assumed a reducing wheel train value of 15 2/25 which means that for every twenty five turns of member 10 only two would be due to the governing gear. Thus, with the main shaft running at 282.6 R. P. M.

$$35 \quad \frac{282.6 \times 23}{25} = 260 \text{ R. P. M.}$$

would be the number of turns obtained from main driving shaft A out of the total number of turns which may be required for member 10. This speed is what I term the extreme "recessive" speed of the differential. By this I mean that if the governing gear, which through member 11 and through the reducing wheels train acts upon member 10, 20 were kept stationary, the differential would still, through the motion it receives from main shaft A, communicate to member 10, 260 R. P. M. out of the total number of turns required by that member at any moment during the building of the bobbin. Thus out of the maximum number of turns acting upon planet wheels 21 and 22, through the gear train meshing with the wheel fixed to member 10, the governing gear will only have to provide a maximum of $308 - 260 = 48$ R. P. M. or 15.8 per cent. For the minimum number of turns $274 - 260 = 14$ R. P. M. or only 5.1 per cent will have to be provided by the governing gear. In other words, instead of being saddled with the entire driving load resulting from the up and down motion, the governing gear, with the new method and modern differentials that is with differentials incorporating a reducing wheel or equivalent

train securing mechanical advantage, will only be called upon to provide for the lifting motion the same percentage of power it has to provide for the bobbin motion. It may be objected that the driving load resulting from the lifting motion is small. However small it may be, it calls for expenditure of power in the form of work on the part of the governing gear the sole function of which should be governing and, although a frame when properly aligned and with a bobbin rail properly balanced, may require only a small amount of power for its lifting motion it is none the less a fact that proper alignment is not maintained and that the load resulting from the binding of the rail in its guides is not unfrequently very considerable. Moreover, in frames with modern differentials the relief of the governing gear is considerable even with the frame working in perfect alignment. Of the total amount of power required to drive a frame, properly aligned and balanced, it may with fair accuracy be assumed that 35 per cent represents the load due to the bobbins and 2.5 per cent the load due to the lifting motion. Taking 60,000 foot pounds as the total power required, the load coming on the governing gear would, with winding gear as constructed at present and comprising the differential mentioned, consist of

$$\frac{60,000 \times 2.5}{100} =$$

1500 foot pounds, due to the lifting motion and

$$\frac{60,000 \times 35 \times 15.6}{100 \times 100} =$$

3276 foot pounds due to the bobbin motion or a total of 3276 plus 1500 = 4776 foot pounds. With my new arrangement the lifting motion load is reduced to

$$\frac{1500 \times 15.6}{100} =$$

234 foot pounds. The total load on the governing gear will then be 3276 plus $234 = 3510$ foot pounds and reduced by $4776 - 3510 = 1266$ foot pounds. In other words, in the case cited the load on the governing gear would, with my method of lifting motion control, be reduced by substantially 26 per cent.

When winding on the bare bobbin in the case cited the maximum rate of up and down motion required is substantially 10.252 inches per minute. Cone 8 will then run at 484.5 R. P. M. and, through reduction gearing, drive shaft 1 at say 207 R. P. M. Wheel 3 may be taken as having a circumference of 9 inches which gives a linear speed of $207 \times 9 = 1863$ inches per minute. $1863 \div 10.252 = 181.7$ per cent represents sub-

70

130

stantially the further reduction required to move the top or bobbin rail at its correct rate. With the new arrangement the lifting motion shaft 1 runs substantially at 24 5 R. P. M. thus $24 \times 9 = 216$ inches per minute will here be the linear speed. $216 : 10.252 = 21$ per cent will be the total reduction required.

In frames as at present constructed the 10 combination of the gear train responsible for the lifting motion is generally such that the reversing gear combined in that train usually consists of bevel gearing; is generally located near shaft 1 or its equivalent and operated from the building motion carried by 15 traverse 40. It will be observed that with such a combination all the backlash present in the train comes into play at every reversal and it will be obvious that my new method 20 provides a means whereby the gear train controlling the lifting motion may be simplified and a much more positive and intimate interdependence of excess speed and up and down motion secured. Indeed, the 25 slow speed of shaft 1 obviates a considerable amount of gearing down and, by operating the reversing motion from a wheel on the shaft carrying pinions meshing with the racks on the bobbin rail, the backlash called 30 into play at every reversal of motion is reduced to an absolute minimum since the few wheels still present in the train, excluding the wheel fixed to the rack pinion shaft, constantly run in the same direction. Any 35 backlash which may still be present in the gearing is thus neutralized as soon as the frame is set in motion. As backlash is no longer present the inevitable period of dwell of the bobbin rail at each reversal will, with 40 the new combination be reduced to almost a vanishing point, thereby ensuring better operation. Further, the velocity of impact at each reversal will be the resultant of the 45 linear and peripheral velocities of the engaging member. With reversing gear as used or proposed at present the speed of the driving member is constant, it generally travels at a considerable peripheral velocity whilst engaging with a member momentarily having none and the engagement between the two members, whether gear or clutch, is always more abutting than a rolling one. Such conditions are not conducive to smooth operation and, in cases where 50 the peripheral velocity of the driving or engaging member is considerable, they render the combination prone to damage.

Now, with epicyclic tumbler gearing according to Figs. 2, 3 and 4, the linear velocity is reduced by the substantially simple harmonic motion of displacement imparted to the pinions (kept in position by links 40 and 50) during the period of reversal; the peripheral velocity, already low as explained, is still further reduced by the epi-

cyclic motion of the pinions 25 and 26 and the combined action make the engagement between the two members more a rolling than a butting one.

With regard to linear speed, in reversing gear as used or proposed at present the linear travel of the engaging member will have to equal twice the depth of the gear or clutch teeth plus the amount of clearance desired. Taking for example the depth of the gear or clutch teeth as .250 inch and the clearance when engaging member is in the middle of its path as .0625 inch either way, then the linear speed from one position to another would be .625 inch during the period reversing gearing 33 travels from one position to another and assuming that said gearing starts, stops and travels with the same velocity. With the epicyclic reversing gear the displacement of the centres of pinions 25 and 26 becomes a simple harmonic motion and this motion allows the magnitude of the displacement to be reduced to .437 inch substantially while keeping the same clearance in the middle position and the same depth of teeth. Now if .437 inch represents the total displacement of the pinion centres and if eccentric travels through an arc of 90° around stud 32 to bring about the reversal, then .437 inch will be half the throw of the eccentric. Further, if the impact takes place at an angle of 50° , then the linear speed at that moment will be

$$\frac{.437 \times 3.14 \times \sin 50^\circ}{4} = .526 \text{ inch} \quad 100$$

again assuming that reversing gearing 33^a oscillates through the same arc as before and starts, stops and travels with the same velocity. The epicyclic gear secures thus an 105 advantage of 12% with regard to linear speed.

With regard to peripheral speed, if wheel 30^a runs constantly in anti-clockwise direction, pinion 26 will run in clockwise direction and pinion 25 again in anti-clockwise direction and both wheel and pinions will run at a low peripheral speed, since it will be only just that required by wheel 23 fixed to the rack pinion shaft. Now when pinion 26 moves from its disengaged position towards wheel 23, it will roll around wheel 30^a in anti-clockwise direction and the epicyclic motion thus produced will reduce the peripheral speed of the pinion and so further reduce the result and speed or velocity of impact when rolling into mesh with wheel 23. A substantially simple harmonic motion of displacement produced by rotating sheave 31 around stud 32 will further cause the epicyclic motion to act in the most desirable manner. Indeed, if eccentric, being fixed to sheave 31 displaces itself through an angle of 90° it is obvious that for the first 45° of travel the rolling 115 120 125 130

of pinion 26 will be very small, whereas the rolling of pinion 25 will be considerable, thereby causing sudden disengagement as required. For the second 45° the rolling of 5 pinion 26 is considerable and of course at a constantly increasing speed but the impact has been made and the further reduction of peripheral speed of pinion 26 which will take place as a result of this rolling creates an 10 engaging movement which may be likened to a gradual starting action. When pinion 25 moves from its disengaged position towards wheel 23, it will roll very little through the first 45°, whereas pinion 26 15 will roll through a considerable angle thereby disengaging itself quickly and momentarily increasing its own peripheral speed as well as that of pinion 25. During the second 45° however the rolling of pinion 26 20 is very small and the epicyclic motion of pinion 25 around the larger pinion 26 will again cause the peripheral speed of the engaging pinion 25 to be reduced considerably and so secure the desired low impact speed 25 and gradual starting action.

The required motion for operating the tumbler gear may be obtained from the mechanism already present in the frame for that purpose by any suitable combination 30 of levers, racks, stops and the like. As an example, a simple and efficient control combination is shown in Figs. 3 and 4. Referring to Fig. 2, arm 52, which carries the grooved pulley 34, is oscillated or operated 35 by a special mechanism, present in every frame, the duty of which is to reverse the direction of travel of the bobbin rail, to move the cone belt or equivalent and to shorten the traverse of the bobbin rail at 40 every reversal. In frames as used or proposed at present the arm 52 or its equivalent generally operates a fairly heavy rod and heavy weights or springs are desirable in order to make the mechanism operate satisfactorily. The arrangement according to 45 Figs. 2, 3 and 4 eliminates the heavy rigid rod and substitutes a light flexible cable 35, rendered rigid in action by counter weight 36. Weight 37 is suspended from cable 38 50 running around pulleys 34 and 41 and thereby balances the pull of weight 36 on arm 52. The lightening and the balancing of the control gear will allow lighter springs or weights to effect the reversal in a proper 55 manner. The arrangement is self-adjusting for wear. By this I mean that stretch in either cable will be taken up automatically by the action of the weights, since the grip of flexible cable 35 around the sheave of 60 eccentric 31 is a friction one and the action similar to that of a capstan. It is advantageous to have the sheave rather large since thereby the cable will suffer less, the contact and therefore the grip, between 65 sheave and cable will be increased and the

balancing weight can be lighter and the lighter the balancing weights the easier the combination will move from one position to another. The sheave on eccentric 31 and the pulley 34 may, if desired, be provided with a spiral groove to prevent wear by friction of cable 35, when coiled in position. A large sheave 31 may involve considerable travel of cable 35. This travel may be obtained from the comparatively small travel 70 of arm 52. Like cable 38, cable 35 is attached to the traverse 40 carrying the reversing mechanism and from there passes round pulley 34, then around pulley 41, then once more round pulley 34 and, from there 75 around jockey 42 and round sheave 31 carrying the eccentric in the manner shewn. This arrangement causes the travel of cable 35 to be 4 times greater than the travel of arm 52 and by sliding pulley 34 up and 80 down in a slot in arm 52, this travel may be easily and minutely adjusted. If a still greater travel were desirable cable 35 might be passed again round pulleys 34 and 41, if less were required the aggregate motion 85 of the combination might be made smaller.

In order to keep the whole lifting motion gearing as simple and compact as possible and to make this gearing a quiet and smoothly operating one, I may reduce the 90 speeds of wheels 17 and 18 provided this reduction is proportionate for either or both. This is of advantage for example in the case of fine rovings where the up and down motion will be much slower although 95 flyer spindles and bobbins run much faster. Thus reverting to my foregoing case where the speeds for wheels 18 and 17 are 308—274 R. P. M. and 260 R. P. M. respectively, they might be reduced to 154—137 R. P. M. and 130 R. P. M. or to 77—68.5 R. P. M. and 65 R. P. M. without in any way impairing the correct operation of the up and down motion. The speeds of shaft 1 would thereby be reduced to either 12 and 3.5 100 R. P. M. or to 6 and 1.75 R. P. M. and less gearing down would be required accordingly.

I further draw attention to the fact that the lead of worm, spiral or like gearing can 115 be modified more easily and much more minutely than spur or bevel gearing because at least one tooth of difference must be made and this generally influences the diameter of the wheels and their centre distances. Worm, spiral or like gearing might therefore with advantage be included in my lifting motion control gear in cases where very minute compensations are of 120 advantage.

I have now shewn that shaft 1, driving the gear train responsible for the up and down motion, may be given a very slow rotary motion and indicated alternative methods for determining the combination 125

of gearing required to obtain the necessary motion with any desired degree of accuracy. I have shewn that shaft 1 may operate the lifting motion correctly in circumstances 5 where the governing gear speed no longer varies inversely as the bobbin diameter. I have also shewn that the reversing motion may be improved by the use of epicyclic tumbler gear and by using flexible cable 10 for controlling it.

Governing gear varies in design according to the material the frames have to work. In frames dealing with jute, flax and the like, expanding pulley and disc friction 15 gear is not uncommon; in frames for cotton and the like hyperbolic cone gear is universal as constituting the most convenient means for sensitive governing. Now governing gear may be made with a speed 20 ratio equal to the bobbin diameter ratio, and in such cases the governing gear will be used to its full advantage. Where the governing gear speed ratio exceeds the bobbin ratio, the excess ratio is wasted, as it never 25 comes into action in frames as built at present. With expanding pulleys and friction disc governing gear, the total displacement of the belt or equivalent member connecting the driving and the driven members 30 is necessarily limited because for great displacements they soon become unwieldy in diameter. Cone gearing on the other hand does not require increase in diameter for increased total displacement, they are made 35 longer and thereby a great travelling distance is secured for the belt and consequently a decided displacement for every speed variation required. Their lengthening 40 also presents the further advantage of flattening their curvature thereby securing a better grip for the belt. Now where a cone gear with a speed ratio of 6 to 1 can be employed for winding bobbins with a diameter of 4 to 1, it will be obvious that 45 with belt displacements similar to those of normal cone gear, the speed variation will be much more decided and more than counter balance the loss of grip due to increased curvature since less duty would be required 50 from it. On the other hand, where a cone gear with a speed ratio of 3 to 1 is used for winding bobbins with a diameter ratio 4 to 1, its curvature would be much flatter as it could be taken more on the asymptote, 55 the grip of the belt would thereby much improve and again more than counter balance the slight extra duty required from it. In any case with my gear the duty of the governing gear would be much lighter than 60 the one it has to perform in frames as built at present. So in all cases where my gear is employed improved operation would result as the governing gear would operate better and more easily.

65 Assuming that the governing gear as em-

ployed at present, whether cone, disc friction or expanding pulley gearing were replaced by another governing contrivance acting upon or combined with the main shaft differential in such a manner that, 70 although capable of securing the correct variation in excess speed for the bobbins it could not operate the up and down motion, my method would provide a means whereby that motion could be obtained. It is conceivable that a variable speed box, controlled by a cam or a similar movable but nonrotating governing gear, might replace the present rotating governing gear and differential and it is obvious that in such 75 cases the lifting motion could only be satisfactorily obtained by my method.

80 From the foregoing it will be observed that in the machine herein described the differential carried by the shaft A controls the rotation of the bobbin 14 by means of the gearing 10—13, and the differential carried by the shaft 1 controls the alternate vertical translation of said bobbin. In the first of said differential systems, the gear 85 15 is the constant speed member, the member 11 the variable speed member, and 10 the recipient of the aggregate motion of the other two members; while in the second differential system, the double gear 17 is the constant speed member, the double gear 18 the variable speed member, and the shaft 1 the recipient of the aggregate motion of the other two members. The two differentials are geared together in such a way that the 90 constant speed member 17 of the translation-controlling differential is actuated by the constant speed member 15 of the rotation-controlling differential, while the variable speed member 18 of the translation-controlling differential is actuated by the recipient 10 of the rotation-controlling differential through the gear 20. It will be seen that at equirotal speed of the constant 95 speed member and recipient of the rotation controlling differential, there will be no rotation of the recipient of the translation-controlling differential.

100 In the operation of the machine, taking for example the form thereof shown in Fig. 2, constant motion is imparted to the shaft carrying the driving cone 7 (Fig. 1) and thence through gearing 16 to shaft A and consequently to gear 15. At the same time, motion is being imparted from cone 7 to cone 8, and thence through gearing 12 to differential member 11, thus imparting to the recipient 10 the aggregate motion of A and 11, which 10 in turn imparts to the bobbin rotating gearing 13. During this 110 time, the constant speed member 15 of the rotation-controlling differential imparts motion to the member 17 of the translation-controlling differential, while the recipient 10 of the rotation-controlling differential 115 120 125 130

imparts motion by means of gear 20 to the variable speed member of the translation-controlling differential, thus imparting the aggregate motion of the members 17 and 18 to shaft 1, which in turn transmits said motion by means of gearing 33—4 to the translation system. It will, thus, be seen that the rotation-controlling differential also produces, through the medium of the second differential, the translational motion of the bobbins, so that the rotational and translational motions of the bobbins are rendered intimately interdependent. By making the translational motion a motion of aggregate character, and by connecting the differentials in the manner herein described, the dual advantage of intimate interconnection of the two bobbin motions and reduction of the load on the translational gearing is obtained.

Having now particularly described and ascertained the nature of my said invention and in what manner the same is to be performed, I declare that what I claim is:—

1. In a machine having a bobbin support adapted to permit rotation and alternate vertical translation of the bobbin, the combination of a differential controlling the rotation of the bobbin, a differential controlling the alternate vertical translation of the bobbin, each of said differentials having a constant speed member and a variable speed member, said differentials being geared together so that the constant speed member of the second differential is actuated by the constant speed member of the first differential and the variable speed member of the second differential received the aggregate motion of the constant and variable speed members of the first differential.

2. In a machine having a bobbin support adapted to permit rotation and alternate vertical translation of the bobbin, the combination of a differential controlling the rotation of the bobbin, a differential controlling the alternate vertical translation of the bobbin, each of said differentials having a constant speed member, a variable speed member, and a recipient of the aggregate motion of the constant and variable speed members, said differentials being geared together so that the constant speed member of the second differential is actuated by the constant speed member of the first differential and the variable speed member of the second differential is actuated by the recipient of the first differential.

3. In a machine of the character described having a lifting motion gear train and a bobbin rotating gear train, a driving shaft, a gear secured to said driving shaft and operating with a constant speed, a member revolvably mounted on said driving shaft, and operating with a variable speed, a gear wheel secured to said member and driving said bobbin gear train, a driven shaft adapted to drive said lifting motion gear train, and differential gearing between said driven shaft and the constant and variable speed members carried by the driving shaft for imparting to said driven shaft the aggregate motion of said members.

In testimony whereof I have signed my name to this specification.

EMILE JOHN WELFFENS.
